METHOD AND DEVICE FOR COLORING MAGNETIZABLE ARTICLES OF MASS PRODUCTION

Wilhelm Magener and Otto R. Barth, Berlin, Germany; said Barth assignor to Willibald von Mikovényi

Application July 9, 1938, Serial No. 218,474
In Germany July 17, 1937

3 Claims. (Cl. 91—60)

Our invention relates to the coloring of metal articles of mass production, such as snap fasteners, safety pins, and the like, as far as these articles consist of magnetizable material.

5 A suitable way of coloring articles of the above kind is employing the well-known spraying method. However, when applying this method to articles of such smallness and lightness, a number of difficulties arise. The air current from 10 the spray gun easily whirls around the articles, thus scratching and wiping the freshly deposited color, and also tends to blow them off the spray rack. A prerequisite for a satisfactory coloring of small articles by spraying, therefore, is to attach them to the supporting rack in order to prevent them from being moved by the spray current. This result could be obtained by providing 15 the surface of the rack with pins or other holding means on which the objects to be colored are 20 to be placed by hand. It is, however, also necessary to reverse the articles on the supporting rack after the upper surface has been colored, in order to now spray the other side. It is evident that such a method which requires 25 repeatedly manipulating each individual article involves expense which in the case of mass products are liable to render the products unmarketable.

The object of our invention consists in providing 30 a method and apparatus for spray-coloring articles of mass production, in particular such as aforementioned, in an easy and inexpensive way which obviates the above difficulties.

The method according to our invention comprises 35 the following sequence of steps. At first the articles to be colored are placed on a magnetizable rack or table in proper position for spraying. Then the rack is magnetized, thereby firmly attaching the articles to the supporting 40 surface of the rack. Now the upper side of the articles is colored by spraying them with a coloring liquid such as paint, varnish, lacquer or the like. After drying of the color, a second magnetizable rack is placed upon the articles so as 45 to cover the articles with its supporting surface. Now the first rack is demagnetized and the second rack magnetized, thereby attaching the articles to the second rack with their colored portion facing the surface of this rack. The second 50 rack, now carrying the articles, is removed from the first rack and the articles are again sprayed, thus coloring their other side. Finally, the second plate is demagnetized for releasing the finished articles.

55 In the following, the invention is further

elucidated with reference to the accompanying drawing showing a part-sectional front elevation of a device for carrying out the aforementioned method.

The device contains a base F having two insulating frames or "beds" B₁ and B₂ firmly attached thereto. Each bed carries a magnetizable plate P₁ and P₂ respectively, each being provided with a magnetizing winding W₁ and W₂ respectively. Plate P₂ is mounted to a lever L pivoted about shaft A on frame F. A handle H forming part of lever L allows removing plate P₂ from bed B₂ and tilting it 180° through the position indicated by broken lines, until it reaches plate P₁ and rests on top of this other plate. 15

The plates P₁ and P₂ are of equal size and consist of iron or another ferromagnetic material of high permeability. In the case of a device for spray-coloring snap fasteners or safety pins, for instance, iron plates having a thickness of 2 to 3 mm. may be used. The outer surface of each plate forming the rack surface proper, is ground. The windings W₁ and W₂ are connected by conductors C₁ and C₂ through a selective switch S with conductors C leading to a current source. Switch S has three operating positions, one for cutting off the current supply, one for energizing winding W₁, and the third for energizing winding W₂. Therefore, only one of the plates can be magnetized at a time. 30

The device is operated as follows. In the position of rest shown in the drawing, a multitude of articles to be colored, for instance 2,000 to 3,000 snap fasteners, are poured on plate P₁ and then evenly spread over the surface of the plate 35 so that all the fasteners lie flatly side by side. Now plate P₁ is magnetized by operating switch S. The fasteners, represented in the drawing by dashes D, thus are firmly secured in proper position for spraying. Now the top side of the fasteners is painted by means of a spray gun. After finishing the spraying and after drying of the paint, the plate P₂ by means of handle H is turned over to plate P₁ until its surface contacts the snap fasteners. Now switch S is again actuated to disconnect winding W₁ and to energize winding W₂. The effect is that now the fasteners while maintaining their proper position are released from plate P₁ and attached to plate P₂. If now plate P₂ is turned back to resume the original position 40 shown in the drawing, the snap fasteners lie properly on this plate now offering their unpainted surface to the spray gun. After finishing the coloring, the current is switched off and the snap fasteners are removed from plate P₂, 45

50

55

for instance by again tilting the plate and thereby throwing the fasteners into a collecting box. The device is now ready for another spray. The coloring of safety pins and other small magnetizable objects is effected in the same way.

5 We claim:

1. The device for spray-coloring magnetizable articles such as snap fasteners, safety pins and the like, comprising a stationary frame, a 10 magnetizable spray rack firmly mounted on said frame, a second magnetizable spray rack pivoted on said frame so as to be movable from a working position onto said first rack, and means for alternatively magnetizing said racks.
- 15 2. The device for spray-coloring magnetizable articles such as snap fasteners, safety pins and the like, comprising two magnetizable racks for carrying the articles to be colored, each of said racks comprising a plate of ferromagnetic material and a winding for magnetizing said plate, 20 said racks being designed to allow placing one of them on top of the other so as to have their

carrying surfaces facing each other, electric means for connecting said windings with a current source, and a selective switch forming part of said means for alternately energizing said windings.

3. The method of spray-coloring magnetizable articles such as snap fasteners, safety pins and the like, with the aid of two magnetizable spray racks, comprising the steps of placing a multitude of said articles on one of said racks, magnetizing 10 said rack so as to firmly attach said articles to said rack, spray-coloring the upper side of said articles, placing said other rack on said articles, demagnetizing said first rack and magnetizing said second rack so as to now attach said articles 15 on their colored side to said second rack, removing said second rack from said first rack, again spraying said articles for coloring their other side, and releasing said articles by demagnetizing said second rack.
